UNITED STATES PATENT OFFICE

1,950,179

ELECTRICAL SEPARATOR

Charles F. Jacobs, Brooklyn, N. Y.

Application August 12, 1931, Serial No. 556,479

4 Claims. (Cl. 173—314)

This invention relates to new and useful improvements in separators for electrical wires. It has especial reference to electrical separators for wires used in the construction of radio transmitter antennæ.

A main object of the invention is to provide a simple, durable, economical efficient separator especially for antennæ lead-in wires which will maintain said lead-in wires a predetermined distance from each other.

A further object is to provide such a separator which will be capable of quick and easy attachment to and dis-attachment from said wires and yet firmly hold the wires in their proper relation when in use.

Further and more specific objects, features and advantages will more clearly appear from a consideration of the specification hereinafter taken in connection with the accompanying drawing which forms part of the specification and which illustrates a present preferred form of the invention.

The invention briefly has particular advantage in two-wire radio frequency feed lines. In such frequencies the purpose is to balance out all voltage and amperage from the lead-in wires and place the useful energy in the flat top or radiating portion of the antenna. This permits the transmitting apparatus to be placed at great distances from the antenna itself, if necessary.

In such an arrangement it is of high advantage and very necessary that the two wires of the radio frequency feed line be kept at equal and uniform distance throughout their entire length. To this end the invention provides a simple, economical and efficient device which will be connected at both ends to the respective wires to provide a firm contact and yet to keep the wires definitely spaced. A number of these separators can be spaced at intervals along the wires. It is, of course, understood that these separators can be employed in other constructions where it may be desirable to keep wires spaced a predetermined distance from each other.

The invention briefly contemplates a body of insulated material having means at opposite ends to receive the wires and with adjustable clamping heads on the ends to press against the wires, said clamping heads being preferably longitudinally movable to clamp the wires and to release them. The heads when in operative position being fastened therein by tightening up on a couple of wing nuts. The device is composed of a very few simple parts which can be readily and economically manufactured and very easily

assembled and disassembled for replacement and repair. The invention in its broad form comprises a bar of insulating material with axially adjustable clamping heads at its opposite ends. These heads are mounted on rods slidable longitudinally in bores in the ends of the bar and these rods are connected adjustably to clamping screws which themselves are adjustable in slots to permit the adjustment of the clamping heads at variable distances from the ends of the bar as desired.

The preferred present form of the invention is shown in the drawing of which:

Fig. 1 is a plan view of the device;

Fig. 2 is an elevation of one of the end clamps with its supporting rod;

Fig. 3 is an end elevation of the clamp and rod;

Fig. 4 is a section taken on the line 4—4 of Fig. 1;

Fig. 5 is a section taken on the line 5—5 of Fig. 1;

Fig. 6 is an end elevation of the device;

Fig. 7 is a semi-diagrammatic figure showing a preferred electrical circuit in which the connector is advantageously employed.

As shown in Fig. 7 the flat antennæ 10 is provided with insulators 11 and 12 and with feed wires 13 and 14, respectively, connected to the flat antennæ on opposite sides of the insulator 11. These feed wires are connected to suitable indicating elements 15 and 16 and to transmitting apparatus diagrammatically indicated by the letter A. In radio frequency circuits as expressed above it is desirable to maintain these feed wires equi-distance from each other to balance out certain energies in the system for the reasons mentioned.

To effect this definite spacing of the feed-in wires I provide a bar of insulating material 17 having metal wire clamping heads 18 and 19 at opposite ends. These heads are supported on the rods 20 slidably in bores 21 in the bar 17. Near the ends of the rods 20 are provided apertures 22 through which clamping screws 23 extend. This clamping screw is provided with a head 24 at one end and a wing nut 25 at the other and is adapted to be adjusted lengthwise of the bar by reason of its slidability in a slot 26 formed in line with the end of the rod 20. The inner face of the clamping head 18 is provided with a wire receiving groove 27 and a corresponding groove 28 is formed on the ends of the bar 17 and registers therewith. Between these two grooves a wire such as feed in wires 13 and 14 may be received. This construction

will permit the feed in wires to be spaced insulatingly from each other and yet firmly gripped. To apply the wires the wing nuts 25 are released permitting the screw 23 to be slid in a given 5 direction, in order to slide the rod 20 and move the head 18 away from the end of the bar thus permitting the wire to be disposed in the grooves. The clamping head and the rod are then moved in the opposite direction to press the head 10 against the end of the bar whereupon the wing nut 25 is tightened, which fastens the elements in this adjusted position. The same construction and operation takes place with respect to the other wire at the opposite end of the bar. 15 The bar may be made of any suitable material preferably non-conducting, such as hard rubber or bakelite. By providing the slot 26 it is possible for the clamping head to be adjusted not only to release the wires and to permit their insertion, but to enable wires of different thicknesses to be employed.

It will be perceived that this device is simple in construction, economical to manufacture, and one which can be very quickly and easily applied to the circuit wires. It is understood, of course, that other wires than those indicated in Fig. 7 can be properly spaced by using my device, but the application shown is one in which the use of my device is of high advantage.

30 The device is simple, compact and will stand considerable use without readjustment or repairs.

While the invention has been described in detail and with respect to a present preferred form thereof it is not to be limited to such details and forms since many changes and modifications may be made in the invention without departing from the spirit and scope of the invention in its broadest aspects. Hence it is desired 35 to cover any and all forms and modifications of the invention which may come within the language or scope of any one or more of the appended claims.

What is claimed, is:

45 1. An electrical separator comprising a bar of insulating material having wire receiving grooves in opposite ends thereof, wire clamping heads dis-

posed in abutting relation against the opposite ends of said bar and having recessed wire receiving grooves therein, rods slidably in bores in said bar and supporting said heads and adjustable clamping screws engageable with said rods to adjust the position of said heads with respect to the ends of the bar, said clamping screws being adjustable along the length of the bar.

2. An electrical separator which comprises a bar of insulating material having wire receiving grooves in opposite ends thereof, metallic wire clamping heads abuttingly disposed against opposite ends of the bar, said heads having wire receiving grooves in alignment with the first mentioned grooves, rods fastened to said heads and slidably in bores in said bar, said bar having transverse slots therein uncovering the inner ends of said rods, and clamping screws adjustably disposed in said slot and engageable with the ends of said rods to clamp said rods in an adjusted position whereby the heads may be adjusted and fixed, as desired.

3. An electrical separator which comprises a bar of insulating material, clamping heads disposed in abutting relation against each end of the bar, rods slidably extending from said heads into bores in the bar, fastening elements on the inner ends of the rods adapted to engage with the bar to clamp the rods in desired positions in the bores, the construction of the bar permitting the movement of the fastening elements with the rods to predetermined desired clamping positions whereby the heads may be adjusted with respect to the ends of the bar to grip a wire between the ends of the bar and the respective heads.

4. An electrical separator which comprises a bar of insulating material, clamping heads disposed in abutting relation against the ends of said bar, rods slidably extending from said heads into bores of the bar, fastening elements on the bar extending transversely thereof and engageable with said rods, said rods being adjustable in the bores to permit the adjustment of the heads with respect to the end of the bar to grip a wire therebetween, said fastening elements being adjustable along the length of the bar.

CHARLES F. JACOBS.
